DESIGN FOR A COMBINATION CHALK AND CIGARETTE HOLDER FOR BOWLING AL- LEY NEWEL POSTS

William Bueche, Cheviot, Ohio

Application October 22, 1937, Serial No. 72,376

Term of patent 3½ years

To all whom it may concern:

Be it known that I, William Bueche, a citizen of the United States of America and a resident of Cheviot, in the county of Hamilton and State of Ohio, have invented a new, original, and ornamental Design for a Combination Chalk and Cigarette Holder for Bowling Alley Newel Posts, of which the following is a specification, reference being made to the accompanying drawing, forming a part thereof.

Fig. 1 is a top plan view of a combination chalk and cigarette holder for bowling alley newel posts showing my new design.

Fig. 2 is a cross sectional view taken on line 2—2 of Fig. 1.

I claim:

The ornamental design for a combination chalk and cigarette holder for bowling alley newel posts, as shown.

WILLIAM BUECHE.
